CLOTHES WASHING MACHINE

Peter Eduard Geldhof, Syracuse, N. Y., assignor
to Easy Washing Machine Corporation, Syra-
cuse, N. Y., a corporation of Delaware

Application November 21, 1932, Serial No. 643,635

1 Claim. (Cl. 68—131)

My invention relates to clothes washing ma-
chines, and more particularly to a novel method
and means for washing clothes.

In washing machines of the prior art of the
reciprocable agitator type, thorough cleansing of
the fabrics being washed was impossible, or if
possible, could not be accomplished in as short
a time as desired because the clothes were not
tumbled about sufficiently and because the clothes
were subjected to no substantial scrubbing action.
During the clothes washing operation also, the
clothes had a tendency to remain substantially
dormant, especially if the vat were well filled with
clothes, so that new clothes surfaces were not being
constantly presented to the scrubbing action of the
agitator. Consequently, the clothes were neither
scrubbed sufficiently nor uniformly. Almost total
reliance for thorough cleansing of the clothes was
placed on the agitation of the cleansing fluid
which has been found to be inadequate.

An object of my invention is to provide a novel
method and means for washing clothes by which
the aforementioned difficulties are overcome and
generally more thorough cleansing of the clothes
is secured.

Another object of my invention is to provide
means whereby clothes are tumbled about and
the entire contents of the clothes washing vat are
subjected to an effective scrubbing action.

A further object of my invention is the pro-
vision of a novel method and means for washing
clothes whereby the cleansing fluid is caused to
pass through and around the clothes, while at the
same time, the clothes are subjected to an ef-
fective scrubbing action.

My invention further contemplates the pro-
vision of means whereby the clothes are sub-
jected to an effective scrubbing action and al-
though substantially suspended in the cleansing
fluid, are moved upwardly and downwardly and
tumbled about in the vat, while the cleansing
fluid in the vat is passed through and around
them.

Other objects and advantages of my invention
will be more apparent from a perusal of the
specification, taken in connection with the draw-
ings, in which:—

Figure 1 is a plan view of my novel agitator.

Figure 2 is a vertical view of the agitator shown
in Figure 1.

Figure 3 is a partial vertical sectional view
showing my novel agitator mounted in a washing
machine.

Figure 4 is a view taken on line 4—4, Figure 3,
55 in the direction indicated by the arrow.

Figure 5 is a view taken on line 5—5 of Figure 3
in the direction indicated by the arrow.

Figure 6 is a view of an alternate construction
in which the agitator is rotated, as well as recip-
rocated.

Figure 7 is a view taken on line 7—7 of Figure 6.

Figure 8 is a view taken on line 8—8 of Figure 6.

Figures 9 and 10 are plan and sectional views
of an alternate form of my novel agitator.

Figures 11 and 12 show another alternate con- 10
struction for an agitator.

Figures 13 and 14 disclose still another alter-
nate form in which the agitator may be made.

In my invention, I provide a novel method and
means for washing clothes whereby the clothes 15
are cleansed by the passage of cleansing fluid
through them, the cleansing fluid being caused
to flow in powerful well-defined currents, first
in one direction, and then in the opposite direc-
tion whereby the cleansing fluid is caused to pass 20
completely through and around the clothes. Fur-
ther, the clothes are effectively agitated and tumb-
bled about so as to expose new clothes surfaces
not only by the turbulent action of the cleansing
fluid but also by the movement of the clothes- 25
washing means itself. Still further, while the
water and clothes are being thus agitated, the
clothes are moved upwardly and downwardly in
the vat and subjected to an effective scrubbing
action.

Referring more particularly to Figure 3 of the
drawings, in a vat 11 which may be of any de-
sired shape and which, as shown in the draw-
ings, comprises a substantially horizontal bottom 12
and vertical side walls 13, an agitator or im- 30
peller 14 is mounted which is adapted to be re-
ciprocated within the vat 11.

The agitator, as shown in Figures 1 and 2,
while it may consist of a single substantially cir-
cular member, is shown as comprising a pair of
substantially circular, irregularly shaped impeller
members 16 and 17. Each of the impeller mem- 40
bers is designed to effect a maximum degree of
scrubbing action on the clothes, and accordingly,
the outer circumference 18 of each of the im-
peller members is made irregular or scalloped,
and on the upper and lower surfaces of each of
the impellers, there is formed a series of circular
projections or steplike formations 19 designed to
cause a rubbing action on the clothes as the agi- 45
tator is reciprocated. Preferably the lower im-
peller 17 is made slightly larger in diameter than
the upper impeller 16 so that the lower impeller
will project beyond the upper impeller and con- 50
tact with the clothes and also so that there will
be a partial overlap of the two impellers. 55

be a greater tendency for the clothes to be carried upwardly and downwardly in the vat when the agitator is reciprocated.

The impellers are mounted on a hub 21 which is preferably formed integral with the impellers and provided with a central bore 22 for receiving a plunger rod 23. The upper portion of the hub 21 is provided with an aperture 24 for receiving a pin 26 and the upper portion of the 10 plunger rod 23 is provided with a plurality of apertures 27 adapted to receive the pin 26 by which the agitator is secured to the plunger rod. A second pin 28 contacting with a flat spot 29 on the pin 26 serves to retain the pin 26 in position and prevent its complete removal.

Concentric with the plunger rod 23 and adapted to be received within an enlarged portion 25 of the central bore 22 is a tubular sleeve 31. The tubular sleeve 31 acts as a guide for the plunger 20 rod 23 through a support 32. Packing 33 is provided around the shaft and retained in compressed condition to prevent leakage along the shaft by means of a spring 34. A nut 36 is threaded internally of the sleeve 31 and retains the 25 packing in position.

The tubular sleeve 31 is flanged at 37 and together with the plunger rod 23, projects through an aperture formed in the bottom 12 of the vat. A housing 38 for the operating mechanism of 30 the washing machine is positioned beneath the vat, and packing 39 is inserted between the co-operating surfaces of the flange 37, the bottom 12 and the housing 38, the entire assembly being retained in position by a flanged nut 41.

The operating mechanism for the plunger rod 23 comprises a motor-driven shaft 42 which is operatively connected to a crank arm 43. The crank arm 43 is pivotally secured to a pitman 44 at 46 and the pitman, in turn, is pivotally connected to an operating lever 47 at 48. The operating lever 47 is rotatably secured to a link 51 at 52 which, in turn, is pivoted at 53 to a bracket 54 riveted or otherwise secured to the housing 38. A link 56 pivoted to a gear case 57 and the operating lever 47 at 58, serves to cause the inner end of the operating lever 47 to reciprocate in substantially a vertical line. It will be apparent that rotation of the motor-driven shaft 42 will cause oscillation of the operating lever 47. A spring 59 secured to the housing 38 and to the operating lever 47, normally urges the operating lever 47 upwardly whereby the load on the motor is decreased during the upward movement of the lever 47.

As more clearly shown in Figure 5, the operating lever 47 is bifurcated to provide arms 61, the ends of which are apertured to receive freely rotatable therein pins 62. The pins 62 project inwardly to engage a trunnion 63 having a central bore 64 to accommodate the plunger rod 23 and having a central bore 66 to accommodate the pins 62. The trunnion 63 is freely rotatable on the plunger rod 23 and is restrained against upward movement on the plunger rod by means of a collar 67 and a pin 68, and against downward movement on the plunger rod by a washer 69 and a nut 71 threaded to the plunger rod.

It will be apparent that when the operating lever 47 is oscillated, the plunger rod will reciprocate within the sleeve 31 and carry the agitator 14 upwardly and downwardly in the vat 11. When clothes and washing fluid are placed in the vat as the agitator is moved upwardly, a partial vacuum will be created at the bottom of the vat and the cleansing fluid will have a tendency to move downwardly along the sides of the vat and

inwardly towards the center thereof. Similarly, when the dolly is moved downwardly, the cleansing fluid will move upwardly along the sides of the vat and inwardly towards the center thereof. The rapid reciprocation of the agitator will cause 5 violent agitation of the cleansing fluid causing it to flow in opposed currents to aid in effecting thorough washing of the clothes by passage of the washing fluid through and around the clothes. The projections on the impeller surfaces will tend 10 to carry the clothes upwardly and downwardly with the agitator and cause them to be tumbled about in the vat, and at the same time, effect a substantial scrubbing action on the clothes. Preferably, the agitator 14 reciprocates entirely beneath the normal level of the washing fluid although during normal operation, the hub may project slightly above the surface when the agitator reaches the maximum height of its movement.

In Figure 6, I have illustrated an alternate form of the construction shown in Figure 3 in which the agitator 14 is rotated as well as reciprocated. This may be accomplished by securing to the plunger rod 23 a pin 73 which moves with 20 the shaft and operates in a slot 74 provided in a plate 76. The slot may be inclined at any angle to the vertical, dependent upon the degree of rotation desired. The plate 76 is secured by nut and bolt assemblies 78 to a bracket 79 depending 30 from the housing 38. When the plunger rod is reciprocated, the movement of the pin 73 in the slot 74 will cause the plunger rod together with the agitator 14 to rotate in one direction upon the upward movement and in the opposite direction upon the downward movement of the plunger rod. This construction will perhaps cause a greater turbulence of the cleansing fluid, a more violent agitation of the clothes and a more thorough scrubbing action. Any degree of rotation 35 may be obtained by changing the angle of the slot 74.

When the agitator is both reciprocated and rotated, the action on the cleansing fluid and clothes therein will be somewhat similar to that described in connection with Figure 3, with the exception that when the agitator is moved upwardly and rotated in one direction, the cleansing fluid will have a tendency to flow downwardly along the sides of the vat and inwardly towards the center thereof and around the vat in one circulatory direction and when the agitator moves downwardly and rotates in the opposite direction, the cleansing fluid will have a tendency to flow upwardly along the sides of the vat and inwardly towards the center thereof, and in the opposite circulatory direction around the vat.

In Figures 9 to 14, I have illustrated other forms of agitators which may be used. The manner of securing the agitators to the plunger rod 23 may be exactly the same as described in connection with Figure 3, the only difference being in the form of the agitator.

The agitator of Figures 9 and 10 is formed with substantially smooth surfaces 81, the lower impeller 17 of which is slightly greater in diameter than the upper for the purpose previously described. The agitator shown in Figures 11 and 12, formed integral with the hub 21, comprises a single disk-shaped member 82, the plane of which lies at an angle to the hub. Figures 13 and 14 show a single impeller agitator with smooth surfaces 83 similar to that shown in Figures 9 and 10. The agitator in this case is made non-round and has projecting portions 84 and indented portions 85 for the purpose of, as dis-

cussed in connection with Figures 1 and 2, securing a better grip on the clothes and a more effective scrubbing action. The agitators shown in Figures 9 to 14 may be reciprocated, as shown in Figure 3, or may be both reciprocated and rotated, as shown in Figure 6.

It will be apparent that various changes and modifications of my invention may be made, without departing from the scope thereof, and I do not desire to restrict myself to the exact size, shape or relation of parts, as various changes may be made within the scope of the appended claim.

What I claim is:

A machine for washing clothes, a vat for containing the washing fluid and clothes to be washed, an agitator mounted in said vat, a plunger rod to which said agitator is secured extending upwardly through the bottom of the vat, said agitator comprising a substantially circular body member, the long axis of which extends at an angle to the bottom of the vat, and means for reciprocating said agitator upwardly and downwardly in the vat. 5 10

PETER EDUARD GELDHOF.
